UNITED STATES PATENT OFFICE.

JOHN R. FARRELL, OF BOSTON, MASSACHUSETTS.

DESIGN FOR BUTTONS.

Specification forming part of Design No. 5,974, dated July 9, 1872.

Specification describing a design for a Button, invented by JOHN R. FARRELL, of Boston, in the county of Suffolk and Commonwealth of Massachusetts.

The nature of my design is fully represented in the accompanying drawing, to which reference is made.

Upon the convex or rounded surface of a button, such as is ordinarily used upon military uniforms, are placed the letters "G. A. R." so as to form a monogram. These letters, which are burnished, are in relief, being slightly raised from the surface of the button, which is unburnished, and are divided by fine lines drawn parallel to each other. The whole is surrounded by a flat burnished rim or border.

This button is designed to be used on the uniforms of the order known as the "Grand Army of the Republic," and may be of any desired size.

I do not claim the form of the button nor the surrounding rim; but

What I claim as my invention is—

A design for a button the center of which is composed of a monogram in relief, formed by the letters "G. A. R." upon a groundwork of fine lines drawn parallel to each other, substantially as shown.

JOHN R. FARRELL.
